BUFFING WHEEL AND METHOD OF
MAKING SAME

George Albert Lyon, Detroit, Mich.

Application September 12, 1950, Serial No. 184,446

8 Claims. (Cl. 51—193)

1

This invention relates to abrading wheels and more particularly to polishing or buffing wheels.

An object of this invention is to provide an improved abrading or buffing wheel as well as a novel way of applying the buffing material thereto.

Another object of the invention is to provide an improved buffing wheel and a novel way of spirally winding strip buffing material under tension thereon.

Yet another object of the invention relates to the provision in a buffing wheel of novel means for attaching a spiral buff strip thereto and for tensioning the same as well as holding the same under tension on the wheel.

In accordance with the general features of this invention there is provided in a buffing wheel structure a circular member having a generally spiral groove therein, a cable wound in the groove and having projecting radially from it a strip of buffing material wound with the cable in the groove, and means for applying and holding the cable and strip to and on the wheel under tension.

In accordance with other features of the invention there is provided in a buffing wheel structure a circular member having a generally spiral groove therein, a cable wound in the groove and having projecting radially from it a strip of buffing material wound with the cable in the groove, the cable having on at least one end thereof a terminal inserted in a slot in an end of the member and detachably held therein, the other end of the cable having a similar terminal adapted to be locked in another slot in the member but provided with means for attaching it to a tensioning cable in the winding of the strip on the wheel.

Other objects and features of this invention will more fully appear from the following detailed description taken in connection with the accompanying drawings which illustrate a single embodiment thereof, and in which:

Figure 1 is an end view taken from one side of a wheel embodying the features of this invention;

Figure 2 is a view similar to Figure 1 but taken from the other side of the wheel;

Figure 3 is a somewhat diagrammatic view showing how a cable with buffed material thereon can be spirally wound under tension in the groove of the wheel;

Figure 4 is a horizontal cross-sectional view taken through the wheel in the direction of its axis;

2

Figure 5 is a fragmentary cross-sectional view taken on the line V—V of Figure 4 looking in the direction indicated by the arrows and showing how one of the cable terminals is held in a slot in an end of the wheel; and

Figure 6 is an enlargement of a portion of Figure 3 showing how a terminal on one end of the cable may be interlocked with a terminal on a tensioning cable used in the winding of the cable and buffing strip on the wheel.

As shown on the drawings:

The reference character 10 (Figure 4) designates generally the core or wheel body of my buffing wheel which has a groove 11 of generally spiral arrangement. It will be noted that the peripheral contour of the groove portion 11 is predetermined to conform with the cross-section of the article to be buffed so that after the buffing material, to be hereinafter described, is 20 in the groove, its surface will be generally that of the article to be engaged.

The body 10 includes end flanges 12 and 13 and a central shaft bore 14 having a spline or keyway for tying the body to the shaft which is to rotate 25 the wheel.

The end flange 13 has a segment shaped slot 16 (Figures 4 and 5) and the end flange 12 has a similar slot 17 (Figures 2 and 4).

In addition, the end flange 13 has transverse 30 cap screws or bolt holes 18 which extend transversely of the slot (Figures 4 and 5). The other flange 12 has similar screw or bolt holes 19 (Figures 2 and 4). A wire cable 20 is adapted to be wound on the groove 11. This cable has wrapped 35 around and secured to it a continuous strip 21 of wrapped or folded buffing material which may be made of any suitable cloth such, for example, as cotton drill material.

One end of the cable, as best shown in Figure 40 5, has firmly attached to it a sleeve type cable terminal 22 with an enlarged flattened eyelet end 23. This terminal 22 is adapted to be inserted in the slot 16 and is held in the slot by means of a bolt or screw 24 extending through the end 23

45 in one of the holes 18. A series of these holes 18 is provided so that terminal 22 can be selectively adjusted to any one of a number of positions in the pie-shaped slot 16. The cable 20 then extends over a kinking shoulder 20a onto the periphery of the body 10.

The other end of the cable 20 (Figures 3 and 55 6) has a similar sleeve type terminal 25 with an enlarged flattened eyelet end 26 formed with a lug or ear 27 for interlocking engagement with a similar lug or ear 28 on a sleeve terminal 28

of a tensioning cable 30 in the winding of the cable on the wheel.

As best shown in Figure 3, after the terminal 22 has been fastened in place in the wheel flange 13, the other terminal 25 is engaged with the terminal 28 of the tensioning cable 30. This tensioning cable 30 may pass over a pulley 31 and may be weighted at 32. While I have shown a weight 32 for putting the cable 30 under tension, any other suitable tensioning means may be used for this purpose.

In wrapping the cable and buffering material on the wheel, the wheel is progressively turned counterclockwise, as shown in Figure 3, resulting in the cable progressively entering the spiral groove 11. During this entire winding operation the cable and buffering strip 21 are under tension so that the same is wound tightly in the groove.

After the cable and buffering strip have been completely wound on the wheel, the terminal 25 is disengaged from the tensioning cable terminal 28 and is inserted in the slot 17 of end flange 12 where it can be bolted to the wheel by means of a bolt or screw 33. It will be noted that at this end there is also a series of holes 19 so that the terminal end 25 can be adjustably secured in position by the cooperating cap screw or bolt 33 passing through one of these holes 19. From the foregoing it is clear that I have provided not only a novel buffering wheel with novel means for fastening the ends of the cable in place, but in addition have provided a novel way of applying the cable and buffering strip carried thereby to the wheel.

It will be understood that modifications and variations may be effected without departing from the scope of the novel concepts of the present invention.

I claim as my invention:

1. In a buffering wheel structure, a circular member having a generally spiral groove therein, a cable wound in said groove and having projecting radially from it a strip of buffering material wound with said cable in said groove, said cable having on at least one end thereof a terminal, and said member having a slot in one end in which the terminal fits, fastening means extending into said member transversely of said slot for attaching said terminal to said member in said slot, the other end of said cable having a second terminal with a shouldered ear for engagement with a similar terminal on another cable for applying tension to the cable during winding on said member, and means for attaching said other end terminal in a slot in another end of said circular member.

2. In a buffering wheel structure, a circular member having a generally spiral groove therein, a cable wound in said groove and having projecting radially from it a strip of buffering material wound with said cable in said groove, said cable having on at least one end thereof a terminal and said member having a slot in one end in which the terminal fits, fastening means extending into said member transversely of said slot for attaching said terminal to said member in said slot, the other end of said cable having a second terminal with a shouldered ear for engagement with a similar terminal on another cable for applying tension to the cable during winding on said member, means for attaching said other end terminal in a slot in the other end of said circular member, said slots comprising generally pie-shaped indentations in the ends of said circular member.

3. In a buffering wheel structure, a circular member having a generally spiral groove therein, a cable wound in said groove and having projecting radially from it a strip of buffering material wound with said cable in said groove, said cable having on at least one end thereof a terminal, and said member having a slot in one end in which the terminal fits, fastening means extending into said member transversely of said slot for attaching said terminal to said member in said slot, the other end of said cable having a second terminal with a shouldered ear for engagement with a similar terminal on another cable for applying tension to the cable during winding on said member, means for attaching said other end terminal in a slot in another end of said circular member, the groove portion of said member having an irregular peripheral contour corresponding with the cross-sectional shape of the object to be buffered and whereby the periphery of the wound strip is given a corresponding shape.

4. In a buffering wheel structure, a circular member having an irregular peripheral surface corresponding in cross section to that of an object to be buffered and having a generally spiral groove in said surface, a cable wound in said groove and having projecting radially from it a strip of buffering material wound with said cable tightly in said groove, said cable having end terminals detachably fastenable in end recesses in opposite ends of said member, and means for adjustably securing said terminals in said recesses with said cable under tension and said buffering strip tightly held by the cable in the groove.

5. In a method of making a buffering wheel comprising a circular wheel member with a peripheral surface of irregular contour corresponding in cross section generally to that of the object to be buffered and having a cable, with a buffering strip projecting therefrom, in a generally spiral groove in said surface, the steps of attaching one end of the cable to an end of the wheel member in a position to enter the spiral groove of the member, progressively winding the cable under tension in the groove to bind it and the buffering strip thereon in the groove and adjustably fastening the other end of the cable to the wheel member so as to hold the cable on the wheel with the wound strip conforming in cross section to the contour of the surface of said member.

6. In a buffering wheel structure, a circular rotary member having an outer peripheral surface of irregular cross-section corresponding generally in cross-section to that of the surface of an object to be buffered and formed to receive a spirally wound cable thereon, a continuous cable spirally wound under tension on said surface from one end of said member to its opposite end and having projecting radially from it a continuous strip of buffering material wound with said cable tightly on said surface, said cable having end terminals detachably fastened at said opposite ends of said member, and means for adjustably securing at least one of said terminals at one of said ends of said member to hold said cable under tension with said buffering strip tightly pressed by the cable against said peripheral surface of said member.

7. In a wheel structure for treating an irregular surface of the character described, an irregularly surfaced core substantially complementary to the profile of the article to be treated and respective end flanges on the core, said core surface having a raised portion intermediately with

the opposite faces sloping toward said flanges and defining valleys between the raised portion and said flanges, and a cable having projecting therefrom surface treating material of substantially uniform width throughout the length of the cable and being spirally wound tightly on said core surface so that the outer periphery defined by the treating material conforms in profile to said irregular surface, said sloping surfaces of said raised portion tending to crowd the cable winding toward said end flanges, and said raised portion and said end flanges cooperating to resist longitudinal shifting of the wound cable on said core.

8. In a wheel structure for treating an irregular surface of the character described, a rotary core circular in cross-section but of irregular sinuous peripheral surface substantially complementary in longitudinal cross-section to the

profile of an object to be surface treated, a cable wound continuously tightly on said surface and having surface treating material of substantially uniform width throughout the length of the cable projecting radially therefrom and wound tightly with said cable on said irregular surface of the core, said core having a recess therein adjacent one end thereof and defining a shoulder, means anchoring the starting end portion of said cable to said shoulder, and means adjustably securing the other end of said cable to said core with said cable and said material wound tightly on said surface and with the periphery defined by the treating material substantially conforming to said irregular surface of the core.

GEORGE ALBERT LYON.
